DESIGN FOR AN AUDIPHONE EAR DRUM PROTECTOR FOR BATHERS

Jack Cohn, New York, N. Y.

Application July 2, 1935, Serial No. 57,489

Term of patent 14 years

To all whom it may concern:

Be it known that I, Jack Cohn, a citizen of the United States, residing at New York, in the county of New York and State of New York, have invented a new, original, and ornamental Design for Audiphone Ear Drum Protectors for Bathers, of which the following is a specification, reference being had to the accompanying drawing, forming part thereof.

In the drawing:

Fig. 1 is a top plan view of an audiphone ear drum protector for bathers showing my new design.

Fig. 2 is a front elevation thereof.

Fig. 3 is a perspective bottom plan view.

I claim:

The ornamental design for an audiphone ear drum protector for bathers, as shown.

JACK COHN.
